(57) **CLAIM**

The ornamental design for a battery accessory for a test and measurement instrument, as shown and described.

DESCRIPTION

FIG. 1 is a top, rear, left, isometric view of a battery accessory for a test and measurement instrument showing the new design in conjunction with a typical operating environment;

FIG. 2 is a top, front, right isometric view thereof;

FIG. 3 is a rear elevational view thereof;

FIG. 4 is a right side elevational view thereof;

FIG. 5 is a left side elevational view thereof;

FIG. 6 is a top plan view thereof and,

FIG. 7 is a bottom plan view thereof.

The broken lines in the drawings depict environmental structure as well as unclaimed portions of the battery accessory for a test and measurement instrument, neither of which form any part of the claimed design.
